Primary Examiner — Christian P. McLean*Assistant Examiner* — Jessica Lynn Devilbiss(74) *Attorney, Agent, or Firm* — Barnes & Thornburg LLP(57) **CLAIM**

I claim the ornamental design for a vehicle, as shown and described.

DESCRIPTION

FIG. 1 is rear elevation view of a vehicle in accordance with my new design;

FIG. 2 is a front elevation view of the vehicle of FIG. 1; FIG. 3 is a left-side elevation view of the vehicle of FIG. 1; FIG. 4 is a right-side elevation view of the vehicle of FIG. 1; and,

FIG. 5 is a top plan view of the vehicle of FIG. 1. The broken lines depict portions of the vehicle that form no part of the claimed design.

1 Claim, 3 Drawing Sheets(56)
